ROCK DRILLING MOTOR

Elmer G. Gartin, Claremont, N. H., assignor to
 Sullivan Machinery Company, a corporation
 of Massachusetts

Application May 31, 1932, Serial No. 614,495

22 Claims. (Cl. 121—10)

My invention relates to rock drilling motors, and more particularly to rock drilling motors of the type employed for the drilling of dry holes from which it is desired to blow the cuttings.

5 An object of my invention is to provide an improved drilling motor of the type specified. Another object of my invention is to provide an improved hole blowing apparatus for use with rock drills, which will involve a minimum of 10 change from a standard motor construction in which the facilities for this operation are not present. A further object of my invention is to provide an improved rock drilling mechanism in which the hole blowing operation may be controlled readily by the normal drill throttle operating devices. Other objects and advantages of 15 the invention will hereinafter more fully appear.

In the accompanying drawing, in which one preferred form and two modifications of my invention are shown for purposes of illustration,—

Fig. 1 is, in the main, a central longitudinal vertical section through a rock drilling motor in which the preferred embodiment of my invention is incorporated, some parts of the motor being 20 shown in elevation and the parts being shown in the position for hole blowing.

Fig. 2 is a fragmentary view showing the same motor with the parts in one of the normal running positions.

25 Fig. 3 is a smaller fragmentary view showing the distributing valve mechanism in a different running position.

Fig. 4 is a transverse section illustrating a 30 modification.

Fig. 5 is an axial section showing a further 35 modification.

Figs. 6 and 7 are transverse sections through the modification of Fig. 5, the sections being 40 taken on planes corresponding to the lines 6—6 and 7—7 of Fig. 5.

The illustrated form of tool has a cylinder 1 which is embraced at its rear end by a head block or casing 2, on which a handle 3, having suitable grasping portions 4, is mounted. At the 45 forward end of the cylinder there is provided a chuck 5 which is adapted to receive the shank or head of a hollow drilling tool 6, the inner end of this shank being positioned to receive blows from a hammer piston 7 which is reciprocable within the cylinder. The hammer piston is actuated by pressure fluid controlled by a pressure actuated valve 8, which is of the type thrown in one direction by constant pressure and in the opposite direction by piston controlled 50 pressure. The valve 8 is herein located in a line-

ment with the piston and at the rear end thereof, within a valve chamber formed in a valve block 9 which is seated in the casing 2. Between the valve block and the cylinder there is provided a plate 10 having a rearwardly projecting boss 11. 5

Pressure fluid is conducted to the tool from any suitable source, through a supply pipe 12 and past a throttling valve 13, later more fully described, at the rear end of the valve block. At its rear end the distributing valve chamber communicates 10

with a constant pressure chamber 14 to which, through an opening 15, pressure is supplied as long as the throttle valve 13 is unseated. The communication of the valve chamber with the constant pressure chamber 14 is through an opening of reduced cross sectional area, and the valve has a contracted portion 15' slideable in the opening and constantly exposed to live fluid pressure in the constant pressure chamber. The valve 15

chamber is provided also with a constant pressure groove 16, to which the live pressure fluid is constantly admitted, during the time when the throttle is open, through one or more longitudinal passages 17, the latter extending from the groove 20 rearwardly to the space to which the throttle valve admits pressure. In the rear position of the valve

25 (shown in Figs. 1 and 3), working pressure is conducted from the pressure groove 16 to the forward end of the cylinder to return the piston, by way of a circumferential valve groove 17', and one 30 or more longitudinally extending passages 18, which open into the forward end of the cylinder through ports 19. In the forward position of the valve, working pressure fluid is conducted to the rear end of the cylinder from the pressure groove 16, through the circumferential valve groove 17' 35 on the valve, to a valve block groove 20, and thence forwardly through the longitudinal passage or passages 21 to the rear end of the cylinder. Exhaust is effected from the rear end of the cylinder 40 when the valve is in its rearward position, through the passages 21, the valve block groove 20, an exhaust valve groove 24, an exhaust passage 25, an exhaust space 26 in the member 2, and a terminal exhaust passage 27. From the forward end of the cylinder exhaust takes place 45 in part through the hollow steel through a bore 28, which is closed by the striking portion 29 of the piston when the latter is in forward position, and in part through port 19, passage 18, and passages 39 connecting the space surrounding the valve portion 15' with the exhaust space 26. When the piston 7 is in its forward position, the 50 reduced portion 29 fills the opening 28 and wholly prevents the escape of air from the for-

ward end of the cylinder to the hollow steel, so that live air admitted through the port 19 will force the piston rearwardly. However, as soon as the portion 29 is withdrawn from the bore 28, the 5 air ahead of the forward end of the piston is connected with the bore of the hollow steel 6.

The valve is reciprocated by differential pressure, means being provided for intermittently applying pressure fluid to the forward or larger area 10 of the valve to lift it intermittently against the constant pressure in the pressure chamber 14. For this purpose, the valve is constructed in the form of a hollow shell, the interior of which is partially filled by the plug 11, previously mentioned, 15 the latter having a groove or passage 32 formed in its side connecting with an intermittent pressure passage 33. The passage 33 is connected by two ports 34 and 35, opening into the cylinder chamber at different points spaced from each 20 other longitudinally of the cylinder, with the cylinder bore; the port 34 being substantially in the same transverse plane as a second port 36, which last is in constant communication with the constant pressure chamber 14 through the longitudinal passage 37. When the piston moves forward, the port 34 is connected with the constant pressure port 36 by means of a reduced portion 38 on the piston, and the valve is reversed by pressure admitted to the large area thereof from the constant pressure chamber through ports 37, 36, 34 25 and passages 33 and 32. On the other hand, when the piston moves backward, pressure fluid is exhausted from the larger area of the valve by the piston uncovering the port 35 and connecting the latter to exhaust through the bore 28 and hollow steel; a sufficient pressure drop following the 30 withdrawal of nose 29 from bore 28 to permit constant pressure on the reduced upper end of the valve to overcome the reduced pressure below the 35 valve.

Through the reciprocation of the valve and the transfer of pressure fluid through the described ports and passages, the hammer piston is caused to move reciprocatively within the cylinder and to deliver its blows against the head of the tool with great rapidity, in a manner which 40 will be obvious from the description given.

When it is desired to effect a more positive cleaning out of cuttings from the bottom of a 45 hole being drilled, this may be accomplished by merely adjusting the throttle valve position. It will be noted, upon reference to Figs. 1 to 3, inclusive, that the throttle valve 13 has a long stem 40 which is provided with three annular 50 grooves: a groove 41 next the valve 13, through which the motor operating fluid supply is conducted; a groove 42, and a groove 43. Grooves 42 and 43 are connected by a longitudinally extending fluid conducting connection, herein in the form of a longitudinal groove 44. A passage 45, extending from the constant pressure chamber 14 to the bore 46 in which stem 40 moves, 55 communicates with groove 42 when the throttle valve is open considerably less than is needed for normal running but not during throttle opening for normal motor operation. A passage 47 connecting with the exhaust chamber 26 also 60 extends to the bore 46 and communicates with the valve stem groove 43 in about the same 65 throttle positions as prevail when groove 42 and passage 45 are in communication. From the 70 description given, it will be evident that with the throttle full open the chamber 14 is under substantially line pressure, but when the throttle 75 is, say, half open, the constant pressure is vent-

ed through passage 45, grooves 42, 44, 43, passage 47, space 26 and exhaust 27. In the closed position of the throttle, no air enters the motor at all. A pivoted lever 49 operates the throttle valve.

From the description given, the mode of operation of this preferred form of the invention will be clear. In the throttle valve position shown in Fig. 1, the distributing valve will be held in rear position, because the constant pressure chamber 14 is vented, and accordingly the air flowing to the forward end of the cylinder 1 will hold the piston back and provide a good blow through passage 17, port 16, groove 17, 10 passage 18 and port 19; it being obvious that the relative areas of passages 15, 45, and 47 and the valve grooves will be suitably proportioned to attain the needed reduction in pressure within chamber 14. It will be noted that in the relative position of the parts shown in Fig. 1, pressure from below the piston passes through 35, 33 and 32 to the space beneath valve 8, and so holds the latter up. When the throttle 13 is moved to full open position, pressure builds up in 15 chamber 14 and the motor runs normally.

In the modification shown in Fig. 4, a throttle valve 13' is carried by a reciprocatory stem 49' which has only a single groove 41'. The venting of the constant pressure chamber 14 is effected through a passage 50, a separate finger-operable, spring-loaded vent valve 51, and an exhaust port 52. With this arrangement, the running motor may be stopped and the hole blown 20 at any time by merely opening the valve 51.

In Figs. 5, 6 and 7 there is used a throttle valve 63, which is both rotatable and reciprocable. The stem 64 is grooved at 65 for the main motor supply, and has an arcuate groove 66 communicable with the passage 67 leading to the space 14 and adapted to connect this space with 25 an exhaust passage 68 upon rotation of the throttle by a special handle 69. Any usual lever or the like, 70, may be used to reciprocate the throttle valve 63 to control the main air supply. It 30 will be seen that the operator will normally control the speed of the motor by longitudinal movement of valve 63, and will effect hole blowing 35 by turning the valve by means of the handle 69.

In each form of my invention, it will be seen that there is provided a very simple, effective 40 arrangement, cooperating with the main distributing valve, and operating by relieving one of the throwing pressures therefor, for effecting 45 hole blowing.

While I have in this application specifically 50 described one form which my invention may assume in practice, and two modifications thereof, it will be understood that these forms are shown for illustrative purposes only and that the invention may be further modified and embodied in various other forms without departing 55 from its spirit or the scope of the appended 60 claims.

What I claim as new and desire to secure by Letters Patent is:

1. A pressure fluid motor comprising a cylinder, a piston therein, a fluid actuated valve controlling the movements of said piston and having an area normally subjected to constant pressure, a throttle valve for controlling the fluid supply to 70 said motor, and means controlled by said throttle valve for venting the pressure supplied to said area to interrupt valve movement.

2. A fluid pressure motor comprising a cylinder, a piston therein, a fluid pressure actuated 75

- valve controlling movements of said piston and having an area subjected to constant pressure during normal motor operation, and controlling means for said motor including a valve member 5 having portions respectively controlling the main supply of fluid to the motor and venting of pressure supplied to said area.
3. A fluid pressure motor comprising a cylinder, a piston therein, a fluid pressure actuated valve controlling movements of said piston and having an area subjected to constant pressure during normal motor operation, and controlling means for said motor including a valve member having portions respectively controlling the main 10 supply of fluid to the motor and venting of pressure supplied to said area and means for reciprocating said valve to effect one of said controlling functions and rotating the same to effect the other.
- 20 4. A fluid pressure motor comprising a cylinder, a piston therein, a fluid pressure actuated valve controlling movements of said piston and having an area subjected to constant pressure during normal motor operation, and controlling means for said motor including a valve member having portions respectively controlling the main supply of fluid to the motor and venting of pressure supplied to said area and means for reciprocating said valve to effect the first named function 25 and rotating the same to effect the second named function.
5. A fluid pressure motor comprising a cylinder, a piston therein, a fluid pressure actuated valve controlling the movement of said piston and having an area subjected to constant pressure during normal motor operation, and controlling means for said motor including a plurality of relatively movable valves respectively controlling the supply of motive fluid to the 30 motor and the throwing pressure acting on said pressure area on said fluid pressure actuated valve.
- 40 6. A fluid pressure motor comprising a cylinder, a piston therein, a fluid pressure actuated distributing valve controlling the movement of said piston and having an area subjected to constant pressure during normal motor operation, and controlling means for said motor including a plurality of relatively movable valves respectively controlling the supply of motive fluid to the motor and the venting of the throwing pressure 35 on said pressure area on said fluid pressure actuated valve.
- 50 7. In a percussive tool, the combination with a drilling motor having a cylinder and piston, a hollow drill steel, a throttle valve for controlling the fluid supply to said motor, means for supplying fluid from said cylinder to said hollow drill steel to effect hole blowing, and a distributing valve for said motor actuated by pressure fluid, of means for controlling said distributing valve to effect hole blowing including a valve movable with said throttle valve for partially 45 venting valve throwing pressure fluid.
- 60 8. In a percussive tool, the combination with a drilling motor having a cylinder and piston, a hollow drill steel, means for supplying fluid from said cylinder to said hollow drill steel to effect hole blowing, and a distributing valve for said motor actuated by pressure fluid, of means for controlling said distributing valve to effect hole blowing including a valve for partially venting valve throwing pressure fluid, said valve having 55 associated therewith a second valve for controlling the main motive fluid supply to said motor, and common operating means for said two last mentioned valves.
9. In a percussive tool, the combination with a drilling motor having a cylinder and piston, a hollow drill steel, means for supplying fluid from said cylinder to said hollow drill steel to effect hole blowing, and a distributing valve for said motor actuated by pressure fluid, of means for controlling said distributing valve to effect hole blowing including a valve for partially venting valve throwing pressure fluid, said valve having 60 associated therewith a second valve for controlling the main motive fluid supply to said motor, and said valves having common actuating means.
10. In a percussive tool, the combination with a drilling motor having a cylinder and piston, a hollow drill steel, a throttle valve for controlling the fluid supply to said motor, means for supplying fluid from said cylinder to said hollow drill steel to effect hole blowing, and a distributing valve for said motor actuated by pressure fluid and having surfaces respectively continuously and intermittently subjected to throwing pressures during normal operation, of means for controlling said distributing valve to effect hole blowing including a valve movable with said throttle valve for partially venting valve throwing pressure fluid from the surface normally continuously subjected to valve throwing pressure.
- 15 11. A fluid pressure motor comprising a cylinder, a piston therein, a fluid pressure actuated valve controlling movements of said piston and having an area subjected to constant pressure during normal motor operation, and controlling means for said motor including a valve member operable to control the main supply of fluid to said motor and, while fluid continues to flow to said motor, to control variably the pressure acting on said area.
- 20 12. A fluid pressure motor comprising a cylinder, a piston therein, a fluid pressure actuated valve controlling movements of said piston and having an area subjected to constant pressure during normal motor operation, controlling means for said motor including a valve member operable to control the main supply of fluid to said motor and the pressure acting on said area, and means for reciprocating said valve member to effect one of said controlling functions and rotating the same to effect the other.
- 25 13. A fluid pressure motor comprising a cylinder, a piston therein, a fluid pressure actuated valve controlling movements of said piston and having an area subjected to constant pressure during normal motor operation, controlling means for said motor including a valve member operable to control the main supply of fluid to said motor and the pressure acting on said area, and means for reciprocating said valve to effect the first named function and rotating the same to effect the second named function.
- 30 14. A pressure fluid motor comprising a cylinder, a piston therein, a fluid pressure actuated distributing valve controlling the movement of said piston, and controlling means for said motor including a reciprocable valve member for controlling the supply of motive fluid to the motor and, while fluid continues to flow to said motor, to control variably the action of the distributing valve.
- 35 15. A pressure fluid motor comprising a cylinder, a piston therein, a fluid pressure actuated distributing valve controlling the movement of said piston, controlling means for said motor including a valve member for controlling the supply of motive fluid to the motor and venting of pressure fluid, said valve having associated therewith a second valve for controlling the main motive fluid supply to said motor, and common operating means for said two last mentioned valves.

- ply of motive fluid to the motor and, while fluid continues to flow to said motor, to control variably the action of the distributing valve, and means for moving said valve member into one position 5 to effect one controlling function and into another position to effect the other function.
16. A pressure fluid motor comprising a cylinder, a piston therein, a fluid pressure actuated distributing valve controlling the movement of 10 said piston, and controlling means for said motor including a valve member for controlling the supply of motive fluid to the motor and the venting of distributing valve throwing pressure, and means for moving said valve member into one position 15 to effect one controlling function and into another position to effect the other.
17. A pressure fluid motor comprising a cylinder, a piston therein, a fluid actuated distributing valve controlling the movement of said piston 20 and having an area normally subjected to constant pressure, and control means having a manual control element and operable at will for venting the pressure supplied to said constant pressure area while fluid is constantly supplied 25 to the latter to interrupt valve movement, said control means being movable by manual pressure on said control element from its inoperative position to its operative venting position.
18. A pressure fluid motor comprising a cylinder, a piston therein, a fluid actuated distributing valve controlling the movement of said piston and having an area normally subjected to constant pressure, and means for venting the pressure supplied to said area to interrupt valve movement while the supply of live pressure fluid 30 to said area is uninterrupted.
19. A pressure fluid motor comprising a cylinder, a piston therein, a fluid pressure actuated distributing valve controlling movement of said 35
- piston and having an area subjected to constant pressure during normal motor operation, and controlling means for said motor including a valve member operable to control the main supply of fluid to said motor and the pressure acting on said area while the flow of fluid to said area remains uninterrupted. 5
20. A pressure fluid motor comprising a cylinder, a piston therein, a fluid actuated distributing valve controlling the movement of said piston, 10 said distributing valve being in the form of a hollow sleeve having a closed end presenting an area on which pressure fluid constantly acts, and means for venting the pressure supplied to said area to interrupt valve movement while the flow 15 of pressure fluid to said area remains uninterrupted.
21. A fluid pressure motor comprising a cylinder, a piston therein, a fluid pressure actuated valve controlling movements of said piston and 20 having an area subjected to constant pressure during normal motor operation, and controlling means for said motor including a valve member operable in one position to control the main supply of fluid to said motor and in another position, 25 while fluid is continuously supplied to said motor, variably to control the pressure acting on said area.
22. A fluid pressure motor comprising a cylinder, a piston therein, a fluid pressure actuated 30 valve controlling movements of said piston and having an area subjected to constant pressure during normal motor operation, and controlling means for said motor including valve means operable to control the main supply of fluid to said 35 motor and, while fluid continues to flow to said motor under the control of said valve means, to control variably the pressure acting on said area.

ELMER G. GARTIN.
